ORGAN CONSOLE

Winsor D. White, Jr., Blowing Rock, N.C., assignor to D. H. Baldwin Company, Cincinnati, Ohio, a corporation of Ohio

Filed July 21, 1965, Ser. No. 86,224

Term of patent 14 years

(Cl. D56—2)

Fig. 1

The dominant features of my new design are shown in solid lines in the drawing, the conventional manuals being continuous across the keyboard as indicated by the dot-dash lines. The back, not shown, is substantially a flat, unornamented surface.

I claim:

The ornamental design for an organ console, substantially as shown and described.
